UNITED STATES PATENT OFFICE.

CHARLES D. SEEBERGER, OF NEW YORK, N. Y., ASSIGNOR TO OTIS ELEVATOR COMPANY,
A CORPORATION OF NEW JERSEY.

CONVEYER.

1,025,316.

Specification of Letters Patent.

Patented May 7, 1912.

Application filed October 18, 1905, Serial No. 283,302. Renewed March 2, 1912. Serial No. 681,172.

To all whom it may concern:

Be it known that I, CHARLES D. SEEBERGER, a citizen of the United States, residing at New York, in the county of New York and State of New York, have invented certain new and useful Improvements in Conveyers, of which the following is a specification, reference being had therein to the accompanying drawing.

10 This invention relates to improvements in conveyers, such as traveling stairways, employed for transporting passengers between different floors or levels.

15 The features and objects of the invention will be pointed out in the accompanying description.

The invention consists of the organizations and arrangements of parts hereinafter particularly described and then pointed out 20 in the accompanying claims.

In the accompanying drawings—Figure 1 is a view in side elevation of a conveyer constructed in accordance with my invention; Fig. 2 is a fragmentary plan view 25 illustrating the relative location of the yoke arms, wheels and connecting links; Fig. 3 is a plan view of the conveyer, the central portion thereof being broken away; Fig. 4 is a view in side elevation of one of the 30 steps, and the associated wheel-carrying yokes and links; Fig. 5 is a sectional view on the line 5—5 of Fig. 4; Fig. 6 is a plan view of the construction shown in Fig. 4; Fig. 7 is a sectional view on the line 7—7 35 of Fig. 1; Fig. 8 is a longitudinal sectional view through a portion of the machine at the top of the incline; Fig. 9 is a fragmentary view, partially in section, illustrating certain driving connections; Fig. 10 is a 40 detail view, partially in section, of one of the bearings of the yoke arms; Fig. 11 is a detail view in side elevation showing the upthrust device for the carrying run; Fig. 12 is a sectional view illustrating the 45 connection between the steps, yoke arms and connecting links; Fig. 13 is a detail sectional view of the floating shunt; Fig. 14 is a diagrammatic view of the conveyer showing 50 a modification of the hand-rail mechanism; Fig. 15 is a plan view of Fig. 14; Fig. 16 is a detail view of the hand-rail drive shown in Figs. 14 and 15; and Fig. 17 is a fragmentary view of the hand-rail for 55 an ascending run of the conveyer.

A series of connected sections or steps

14 is adapted to travel upon the tracks or bearing surfaces 15 and 16, which are illustrated diagrammatically in Fig. 1. These tracks, in the present embodiment of the invention, are on different levels on the 60 inclined portion of the run of the conveyer, the tracks 16 being above the tracks 15, and at the upper and lower levels they are in substantially the same horizontal planes to form landings. On the incline the sections break into step-like formation with their tread surfaces in parallel planes, while at the landings the steps have their tread surfaces in the same horizontal plane. At the 65 end of the upper landing 17 the tracks are curved to form an end-carriage or reverser at 18 for the steps passing from or to the upper inclined transporting run of the conveyer, and then sweep upwardly under the landing 17, as shown by the upper track 19 70 and lower track 20, to a suitable point substantially under the head or top of the upper run, whence they extend in substantially the same level, as shown in Fig. 7, to provide a way for the return run of the conveyer. At the bottom of the incline the tracks 19 and 20 merge with the tracks 15 and 16. When the conveyer is to be used 75 for descending transportation, it is desirable to make the break between the steps as they descend over the curve at the top of the incline more gradual than is necessary at the bottom curve; for this reason the curve at the top is longer than the bottom curve.

Throughout the entire cycle or course in the type of machines here disclosed the tracks are in parallel vertical planes, and the associated tracks on each side of the machine are preferably made in integral 80 castings of convenient lengths so that they may be readily and accurately assembled. The tracks are preferably carried by suitable brackets 21, which may be secured by any suitable angle bars to the supporting 85 structure. The tracks at the opposite sides for both the upper transporting and lower return runs at the top of the incline, which is usually known and designated as the throat of the machine, are preferably made 90 of a single casting or as one assembled piece 22, as shown in Fig. 8. This casting or section carrying all of the tracks at the throat of the machine, including the curves connecting the incline and horizontal tracks, 95 100 105 110

insures accuracy in erecting and assembling the parts, which is of especial importance at a point where the steps change their direction of movement as from incline to horizontal or vice versa, and also furnishes a guide for the gradient of the other portions of the tracks on the incline. These castings 22 may be made complete in the shop with the utmost accuracy, and consequently when erected, the proper relation of the curved tracks, one to the other on the same side of the machine, is definitely assured. It is obvious that the tracks at the bottom of the incline may also be cast in one piece for the same general purposes.

Each step is composed of a suitable frame 23 having a tread and riser, and is provided with an axle bar 24, the ends of which extend beyond the ends of the step, as shown in Fig. 6. Each step has a carriage or yoke, having front and rear arms 25 and 26, mounted on the ends of its axle bar, and the arms provide bearings for the front and rear wheels 27 and 28, coöperating with the tracks 15 and 16, respectively. Links 29 and 30 connect the axle bars of adjacent steps, and these links are in the form of racks having an equal number of teeth, one end tooth on each link being on the center line of the axle bar, as clearly shown in Fig. 4. Motion is communicated to the steps through the medium of the links.

A transverse shaft 31 is suitably journaled on the supporting structure, near the bottom of the incline, and this shaft is provided with pinions 32 which mesh with the links of the return or idle run or stretch of the conveyer, as shown in Fig. 1. The shaft 31 may be driven in any suitable manner, as through the medium of a suitable motor 33. At a suitable point between the oppositely moving runs of the conveyer and preferably near the head of the incline, a transmission shaft 34 is suitably journaled and provided with pinions 35 which engage the links of both runs, as clearly shown in Fig. 8. The conveyer being driven by the pinions 32 motion is imparted through the medium of the lower run to the pinions 35, which by reason of their engagement with the upper run serve as a transmission drive for that run or line. These idlers 35 being located near the top of the incline and engaging the transporting run of the conveyer, serve to pull the steps up the incline, in ascending, the pinions 32 driving the steps around the curves at the bottom of the conveyer. In other words power is applied, in driving, by putting the links in compression, the pinions 32 pushing the links up the incline when the conveyer is employed for ascending, and the pinions 35 pushing them down when the conveyer is driven in the opposite direction.

By arranging the reverse tracks 19 and

20 under the upper landing so that they rise in a curve to a point under the top of the incline, the throat of the machine is narrowed at this point so that the tangential run is higher up the incline on the return line and the idlers 35 may be located nearer the top of the incline than would otherwise be possible. Furthermore, by narrowing the throat of the machine as described I am enabled to employ transmission idlers of minimum diameter, thereby avoiding the use of reduction gearing such as would be necessary with idlers of large diameter.

The idler shaft 34, in the present embodiment of the invention, is journaled in bearings 36, on a cross-frame 37 which may be in the form of an integral casting or one assembled piece suitably secured at its ends to the supporting structure between the tracks, as clearly shown in Figs. 8 and 9. This frame 37 is provided with suitable openings for the idlers 35, which are sufficiently wide to engage both the links 29 and 30, which as shown in Fig. 7 are in parallel lines. By employing an intermediate supporting frame for the transmission shaft, this shaft need not extend through the girders and so does not interfere with the tracks in any manner. By locating the cross-frame upon the track-section, the linkage is more readily brought into correct relation to the idlers in assembling the machine to insure the necessary meshing of the parts.

Referring particularly to Figs. 4, 5, 6 and 12, it will be observed that the yoke is fixed to the step. This may be effected in any suitable manner. In the present instance each yoke is provided with an inwardly extending hub 38 adapted to receive the end of the associated axle bar, and is located thereon and fixed thereto in any suitable manner, as by a pin 39. The frame of the step has a boss 40 which receives the axle bar, and any suitable means, such as a pin 41 passing through the said boss and axle bar, secures the step to the bar. The links 29 and 30 connect alternate pairs of axle bars, as shown in Fig. 2, and are arranged in the form of male and female links. Each end of the male link 29 is provided with a sleeve 42 extending outwardly therefrom and receiving the hub 38 of the associated yoke, and each female link 30 is provided with a collar 43 at each end pivoted on the sleeves 42 of adjacent male links, the yoke being connected with the step through the pivotal center of the links. Suitable washers 44 are provided to reduce friction between the parts. These washers are preferably in the form of lubricating bushings. The step-frames, yokes, and axles are tied together for greater security by a tongue 45 on the hub of each yoke seated in a suitable recess or slot in the boss 40 of the associated step-frame; by

this construction the step and yokes are practically a unit, and free to revolve in the sleeves of the links or allow the links to revolve about this unitary construction in 5 passing the angles or turning through the ends of the machine.

While the axle-bar of each step is shown as continuous, that is to say, as extending from one yoke to the other, it is obvious 10 that, as the chief function of the axle-bar, is to afford the means of locating the step and yoke, that portion of the axle-bar between the ends of the step-frame might be removed if desired, although by employing a continuous 15 axle-bar it adds to the general strength of the construction.

As clearly shown in Figs. 2 and 12, the linkage is pivoted between the step-frames and yokes, and the wheels on the yokes are 20 outside of the linkage, the axle extending through the step-frame, links and yoke. By having the linkage at the side of the steps, the dimension from the wheel base to the tread is much smaller than it is where the 25 links are placed under the steps owing to the clearance usually required for the riser in this latter construction. Furthermore, by this arrangement the steps are left free to turn over when passing around the ends, so 30 that their treads may be uppermost on both runs whereby the machine may also be used for transportation upon its return run if desired.

The front arm of each yoke is shorter 35 than the rear arm, whereby the tracks on the incline may be located nearer together requiring less depth of girder. The axle or line between the joints of the linkage is in advance of the center of the tread when 40 viewed looking up the stairway, and the wheel base is wider than the tread, so that the passenger's weight is practically carried by the wheels on the long arms, which extend beyond the riser of the step, and his position within the area of the carriage is insured 45 so that stability of the step is provided and all tendency of the step to tilt is obviated. Also, by making the rear arms of the yokes longer than the front arms, the 50 step may be made wider so as to confine the foot-space more to an area between the lines of its riser and axle, and by this construction the overhanging nosing will be prevented 55 from striking the foot of the passenger.

The yoke-arm 26 for the rear wheel at each end of the step is bent or curved laterally to pass over the track of the front wheel, as clearly shown in Figs. 5 and 6, diverging at its free end from the vertical 60 plane of the other arm, the inner portion of the arms being in substantially a common plane and the outer or wheel carrying portions or ends being in parallel vertical planes. By this means a straight yoke, that 65 is, one having its arms located in the same

horizontal plane can be employed whose wheels coöperate with tracks on different levels, instead of employing an angular yoke coöperating with tracks on the same level.

The carrying wheels may be mounted on 70 the yoke-arms in any suitable manner, as for example, as shown in Fig. 10. As there illustrated, the yoke is provided at each end with an outwardly extending tubular bearing 46, the wheels being retained on such 75 bearings by means of a washer 47. This washer is provided with a barrel 48 which is seated in the tubular bearing, which is preferably integral with the yoke, and secured therein by suitable means, such as a cotter 80 pin 49. This cotter pin passes through the yoke, which forms the base of the bearing, and the barrel, being thereby located back of the wheel and away from the free end of the bearing. This means for securing 85 the wheels on the bearings provides a positive lock for the wheel-retaining washer, and also enables the wheels to be accurately located in assembling the parts; the cotter pin also prevents the washer from turning. 90 The barrel is reduced in diameter between its ends so as to form with the associated bearing a lubricant chamber, the escape of the lubricant being prevented by the enlargements 50 which snugly fit the inner 95 wall of the bearing. To increase the capacity of the lubricant chamber the barrel may be recessed as shown. The lubricant passes to the wheel through a suitable aperture for this purpose. 100

In linkage of this construction the resistance of the transmission pinions exerts an overturning action as the end or last tooth of each link on the return line leaves the pinion due to the driving tension in the links. This causes a tendency for the other end of the link to rise, and in order to prevent this motion I employ an upthrust device in association with the pinions, which consists in the present instance of a suitable guide or rail 51 located below the pinions, there being one on each side, with reference to the direction of motion of the steps. The upthrust is so related to the pinion that at least the leading tooth of each link is beneath the upthrust when the end or last tooth is in engagement with the pinion. The rail 51 is shown as continuous, although it might be in sections. By making it continuous, however, it serves to prevent kinking of the links while under compression in case any extraordinary resistance is offered to their movement. I also employ an upthrust for the links of the carrying line of 110 steps in association with the transmission 115 pinions, as shown in Figs. 7 and 11, it being understood that each side may be thus provided, and in the present embodiment these upthrusts are placed over the female links as the male links are under the curtain 52, at 120 125 130

the ends of the steps, as shown in Fig. 7, although if desired the upthrusts may be placed over both sets of links. This upthrust is formed by a suitable guide, such as 5 the track 53, which is mounted on an adjustable bracket 54 secured to the supporting structure and overhanging the tracks 15 and 16, as shown in Fig. 7, so as to support the upthrust track directly over the line of 10 movement of the female links. As shown in Fig. 11, the collars of the links 30 are provided with bosses 55 having flat contact surfaces. The upthrust track is held in such position that under normal conditions the 15 bosses just contact the track. In order to compensate for wear the track is made adjustable, and to this end the bracket 54 has ears 56 through which bolts 57 pass which are in threaded engagement with the track 20 53. The track may be provided with suitable elongated slots through which bolts 58 pass and by loosening the bolts 58 and turning the bolts 57 the track may be adjusted vertically as desired and then secured in its 25 adjusted position by tightening up the nuts. The upthrusts being located over the pinions 35, the overturning action of the pinions on the enveloped links is prevented so that they are held in proper relation to the 30 pinions.

The bosses of the female links are offset or to one side of the center of the collars of the links, being located within the space between its pivot centers, to avoid being elevated 35 above the plane in which they normally move under the upthrust when, for example, the advanced end of the links changes direction of movement or enters the curve at the top of the incline. As a further precaution, 40 however, to accommodate such action and to avoid binding, the end of the upthrust track is made yielding and provided with an expansion spring 59, Fig. 11, which serves to resist any pressure exerted against the same 45 by the links. The opposite end of the upthrust may also be curved upwardly, as shown in Fig. 11, to guide the bosses under the track in the event that the links are elevated out of their normal position when they 50 reach the track. In order to accommodate the upthrust to a conveyer adapted to transport in either direction, both ends may be made yielding and turned upwardly, as shown in Fig. 11. In order to reduce the 55 friction due to the engagement of the bosses 55 with the upthrust track the contact surfaces of such bosses may be provided with lubricant cavities. While in the present instance the upthrusts are located over the 60 female links, such links being provided with the bosses 55, it is obvious that the upthrusts may be located over the male links, in which case the latter would be provided with such bosses; or by locating the upthrusts over both the male and female links 65

both sets of such links might have the bosses 55, as shown in Fig. 4. It is also obvious that instead of having a boss at each end of a link each link may be provided with a continuous boss.

Upthrusts of suitable form may be provided in connection with the driving pinions 32. If short upthrusts are employed they are suitably located with reference to the direction of movement of the steps. If 70 desired the upthrusts may be continuous.

In the present embodiment of the invention, I have shown the linkage arranged with the teeth of each run toward the teeth of the other run, that is, directed inwardly, and in 75 describing the upthrusts I have treated the links as arranged in this manner. It is obvious, however, that the linkage may be reversed, having the teeth directed outwardly, and that under such conditions the coöperation 80 of the upthrusts and links would be the same except that the position of the upthrusts would merely be reversed.

Suitable balustrades 60 may be employed 85 and where it is desired to provide narrow 90 steps, in order to economize space, these balustrades may be widened out above the treads by being arranged in oblique planes or inclined outwardly, as shown in Fig. 7, so as to increase the appearance of spaciousness of the machine having narrow 95 steps. At the lower ends the balustrades 100 60 are preferably provided with vertical extensions providing the curtains 52 which depend below the tops of the steps, as shown in Fig. 7, where a riser is illustrated, so as to prevent the foot of the passenger slipping off the ends of the steps, and the male links are located under these curtains. By 105 locating the male links 29 under the curtains 52 the width of the machine is reduced thereby adding to the compactness of the machine which is important when the available space for installation is limited. One balustrade may be deflected or extended 110 across the landing of the conveyer to provide a stationary shunt, as indicated at 61 in dotted lines in Fig. 3, and this shunt may be of any suitable character, such as that to be hereinafter described. I may provide 115 a similar shunt 61 at the opposite end, so that which ever way the conveyer is running a shunt will be located at its exit. By this arrangement, that is to say by providing two side landings, the conveyer is made reversible so that it may be used to transport 120 in either direction. A hand-rail 62 is also employed, being in the present instance, as shown in Fig. 7, elliptical in cross section, with the under face cut out to adapt it to 125 fit on the guides, the inturned edges, provided by the cut out portion, being located at the opposite sides of the balustrade, as shown in Fig. 7. The hand-rail, in the arrangement shown in Figs. 1 and 2, passes 130

around a horizontal pulley 63 fixed to a vertical shaft 64 at the side and end of the lower landing, and travels parallel with and in front of the lower shunt 61, to the opposite side of the conveyer; thence passes along the balustrade 60, the upper end of which provides a guide, as shown in Fig. 7, up the incline, to and over a vertical pulley 65 at the top of the incline and from such pulley 10 travels across the upper landing portion parallel with and in front of the upper shunt 61 to a horizontal pulley 66, which is fixed to a suitable vertical shaft 67 at the side and end of the upper landing portion. 15 From the pulley 66 the hand-rail passes around an angularly disposed idle pulley 68 located over the upper landing portion of the conveyer back of the shunt 61, and by which it is deflected to a vertical pulley 69. 20 From the pulley 69 the return stretch of the hand-rail passes over an idler 70 to a vertical pulley 71 at the opposite end of the machine, around such pulley to and over an angularly disposed idle pulley 72 which deflects the hand-rail to the pulley 63. As 25 shown in Figs. 1 and 3 the hand-rail driving mechanism and deflecting pulleys at each end of the machine are located over the steps at the associated landing and back 30 of the stationary shunt thereat.

Means are preferably provided for maintaining the proper tension of the hand-rail. To this end one or both of the pulleys 69 and 71 may be provided with any suitable 35 form of tightener, such as an automatic tightener, as indicated at 73 in Fig. 3, in which a counter weight 74 is employed for sliding the pulley 69 or 71 to take up the slack of the hand-rail. By this means the 40 hand-rail is automatically tightened without changing the direction of flexure thereof.

The under or inner surface of the hand-rail is the tractive surface, and the elliptical form of the rail admits of deflection by 45 the pulleys on its tractive surface, owing to the fact that one side of the ellipse is cut away. It is obvious that the rail could not be run with its hand-grasp surface against the pulleys without subjecting it to deflections and strains which would impair its 50 usefulness and render it impossible to keep it upon its guides, and also give it the appearance of wear. The hand-grasp of the rail should be kept in as perfect condition 55 as possible, free from dirt, etc. Consequently contact of the hand-grasp surface with the pulleys and other parts should be avoided. With the arrangement shown, and the employment of the elliptical form of 60 hand-rail, the objections pointed out are avoided, the hand-grasp surface of the rail never coming in contact with the pulleys, guides or other parts. By locating the hand-rail where it is deflected across the landing 65 in front of the shunts 61 the deflected por-

tion of the hand-rail will act as a traveling shunt to direct the passenger from the conveyer before the body comes into contact with the associated stationary shunt.

As shown in Figs. 3, 14 and 15, a second 70 hand-rail 75 is located at the opposite side of the conveyer from the hand-rail 62 and this hand-rail where the shunt is employed at both ends of the machine terminates at the ends of the incline so as to provide suitable spaces for passengers to get on and off of the conveyer. This hand-rail 75, in the present embodiment of the invention, as 75 shown in Figs. 14 and 15, passes from an angularly disposed pulley 76, located at the 80 bottom of the incline, along the adjacent balustrade, as shown in Fig. 7, to a vertical pulley 77, at the top of the incline. It then travels from the under side of the pulley 77 back to an angularly disposed idler 85 78, thence upward to a vertical idler 79 located between the idler 78 and pulley 77, then to a vertical pulley 80, located under the idlers 78 and 79 and from which it passes to the pulley 76. The idler 79 rotates in a plane parallel with the plane of the pulley 77 so as to prevent interference of the oppositely moving portions of the hand-rail where they cross, and the angular idler 78 serves to deflect the hand-rail from 90 the plane of one of such elements to the other. The pulley 80 is of course in the same plane as the idler 79, the angularity of the pulley 76 serving to return the hand-rail to the plane of the pulley 77. The idler 100 78 may be adjustably mounted in the same manner as the idlers 69 and 71 in order to provide for taking up slack in the hand-rail 75 so that the latter may be maintained at 105 the proper tension.

The hand-rails 62 and 75 are driven at practically the same speed as the conveyer. The return stretches of both hand-rails may be guided by guides 81 suitably carried on the supporting structure. As clearly shown 110 in Fig. 7 the hand-rails over-hang the tops of the balustrades, thereby guarding the sides of the transporting run and affording contact surfaces for the body of the passenger who being on the conveyer moves at substantially the same speed as the hand-rails.

Where the conveyer is employed for ascending only, the drive for the hand-rail may be located at the upper end of the run, so as to pull the hand-rail along the guide 120 and prevent slack at the portion of the rail exposed to the passenger. Where, however, the conveyer is designed to be reversible or travel in either direction, as in the present embodiment of the invention, it is desirable 125 to also drive the hand-rail at the lower end of the machine, as otherwise the part of the rail exposed to the passenger in descending would be the slack from the upper drive and consequently it could be readily held 130

back by any one disposed to do so. The driving connections may be of any suitable character. In the present instance, for the top drive, the shaft 34 is provided with a sprocket wheel 82 which communicates motion through the medium of a driving chain 82^a (shown in dotted lines in Fig. 9) to a sprocket wheel 83 fixed on the shaft 84 suitably journaled on the sides of the supporting frame. The shaft 84 is located at a point where it can extend through the track castings without interfering with the tracks. The shaft 84 at one end is provided with sprocket wheels 85 and 86. The sprocket wheel 85 communicates motion to the pulley 65 through the medium of a chain 87, while the sprocket wheel 86 drives a chain 88 (Fig. 1) which engages a sprocket wheel 89 fixed to a cross shaft 90 which in turn communicates motion to the pulley 66 at the upper landing through the medium of suitable gearing, such as the bevel gearing 91, as shown in Fig. 3. For the bottom drive for the hand-rail, as shown in Figs. 1 and 3, a chain 92 receives motion from a suitable sprocket wheel (not shown) fixed to the shaft 31 and drives a sprocket wheel 93 on a cross shaft 94 which drives the pulley 63 through the medium of suitable bevel gearing 95. By this arrangement the drives for the upper and lower ends of the hand-rail 62 are separate, and the rotating members or pulleys 63, 65 and 66 which engage the hand-rail to drive the same are located in different planes, the pulleys 63 and 66 being in horizontal planes and the pulley 65 being in a different or vertical plane.

Referring to Figs. 9, 14 and 15, illustrating the drive for the hand-rail 75, it will be seen that a sprocket wheel 96, fixed to the opposite end of the shaft 84, communicates motion to the upper pulley 77 through the medium of a suitable connection, such as a chain 97, while power is applied to the lower end of the hand-rail 75, through the medium of a suitable connection, which consists in the present instance of a chain 98 receiving motion from the shaft 31 and transmitting it to a sprocket wheel 99 fixed with a sprocket wheel 100 which communicates motion to the pulley 80 by means of a chain 101. By reason of the arrangement of the drives described each hand-rail is drawn or pulled along the balustrades in either direction of its movement.

In Figs. 14 and 15 I have shown a modified arrangement of hand-rail mechanism providing traveling shunts crossing the landing portions of the conveyer, which differs from that shown in Figs. 1 and 3 only in the arrangement and location of the driving mechanism. In the embodiment shown in Figs. 14 and 15, the hand-rail, designated 102, passes from a horizontal pulley 103,

which is slightly wider than the conveyer and located over the end of the lower landing, across the lower landing to form the traveling shunt 104, then travels along the balustrade to a vertical pulley 105 at the top of the incline, thence across the upper landing, as at 106, to a horizontal pulley 107 similar to the pulley 103 and located over the end of the upper landing. From the pulley 107 the hand-rail 102 passes, as at 108, to an angularly disposed pulley 109 which deflects it to the plane of a vertical pulley 110 located at the side of the conveyer. From the pulley 110 the rail passes to and over an idler 111, at the top of the incline, then down the incline, as at 112, to and under an idler 113 at the bottom of the incline, and then around a pulley 114 and idler 115, corresponding to the pulley 110 and idler 109, respectively. From the idler 115 the hand-rail passes to the pulley 108. In the construction illustrated both pulleys 103 and 107 are driven. For the upper drive a chain 116 receives motion from the shaft 84 and transmits it to a sprocket wheel 117 to the shaft of which is fixed a pinion 118. This pinion drives a gear 119 on the shaft 120 of which is fixed the pulley 110; and suitable gearing, such as the bevel gearing 121, transmits motion from the shaft 120 to the pulley 107, as more clearly shown in Fig. 16. The driving connection for the pulley 103 is similar to that for the pulley 107, except that the sprocket wheel for the lower drive, corresponding to the sprocket wheel 117, is driven by a chain 122, which receives motion from the main drive shaft 31. Either or both of the idlers 109 and 115 may be mounted in the same manner as the idlers 69 and 71 in the arrangement shown in Figs. 1 and 3 for the purpose of maintaining the proper tension of the hand-rail and to avoid slack. While in the construction shown in Figs. 1 and 3 the take-up idlers and deflecting pulleys are located over the ends of the conveyer, in the embodiment of the invention shown in Figs. 14 and 15 the driving connections with the exception of the gearing 121 and including the take-up idlers and guide pulleys are located at the side of the conveyer.

While I have referred to sprocket connections for driving the hand-rails I do not limit myself in this particular as it is obvious that other forms of driving connections may be employed with the same results.

Where the conveyer is designed for ascending only, no exit shunt then being required for the lower end, the hand-rail at each side may be arranged as shown in Fig. 17. As there illustrated, the hand-rail passes from an idler 123 at the lower landing up the incline to the upper landing and on its return run passes around pulleys 124,

125, and 126, similar to 78, 79 and 80, respectively, in Fig. 14. In order to take up slack one of the pulleys, as 124 may be in the form of an adjustable or take-up pulley

5 similar to the pulley 78.

Referring to Fig. 13, it will be seen that the shunt consists of an upper member or frame, which is the stationary shunt 61 heretofore referred to, and a lower member 10 127. Preferably the member 127, which may consist of a suitable plate standing on its edge, bears upon the steps forming the horizontal landing so as to float thereon. In the present instance the frame 61 is provided with vertical slots, one of which is 15 shown and designated 128, through which project suitable headed pins 129 which are fixed to the plate. A guard strip 130 secured to the frame 61 overhangs the upper 20 edge of the plate 127. The slots 128 are of sufficient length to permit of the necessary rise and fall of the float, due to variation in or unevenness of the tread surfaces of the steps. With this construction the float 25 is supported vertically by the tread surfaces of the steps and laterally by the shunt 61 and guard 130.

In order to guard the leading wheels of the steps, that is to say to prevent them 30 from rising up from the track, I provide guard rails at suitable points, such as 131, 132 and 133, shown in Fig. 1 in dotted lines. The guard 131 is suitably secured in position and located at the point where the conveyor passes from the incline to the horizontal in descending and over the track 16. This guard compels the wheel which then leads, as 28, to follow through the curve 35 down to the horizontal track. The guard 40 132 is located at the end of the lower horizontal landing and has the same function as the guard 131. The guard 133, which is located under the tangential curved stretch 45 under the upper landing and above the track 19 to the curvature of which it conforms, serves to retain the wheels 28 on the track, 50 overcoming their tendency to leave the same under the tension in the linkage.

At the upper landing, as each step passes 55 from the horizontal to enter the end carriage, or vice versa, the back nosing of the step rises slightly above the floor of the landing. This is in harmony with the design, as the shunt is so located that the free 60 end of the landing where this rising occurs is inclosed or covered by the shunt.

Having described my invention, what I claim is—

1. In a device of the class described, an 65 inclined conveyer having oppositely moving runs, a drive applied to one run, and connections between the runs to utilize one run as a medium for applying power to the other run.

2. In a device of the class described, an

inclined conveyer having oppositely moving runs, driving means engaging one run, and an idler engaging both runs to drive the second run.

3. In a device of the class described, a 70 connected series of steps arranged in oppositely moving inclined runs, a drive located near the base of the incline and engaging the idle run, and idlers located near the top of the incline and engaging both runs to 75 transmit motion to the transporting run.

4. In a device of the class described, an endless inclined conveyer having oppositely moving runs and comprising a series of 80 steps and links connecting the steps, and driving means consisting of driven pinions 85 engaging the links of one run and idler pinions engaging the links of both runs.

5. In a device of the class described, an 90 endless conveyer having ascending and descending inclined runs and comprising an endless series of steps and links connecting the steps, driving pinions engaging the links near the lower end of the descending run, and idler pinions driven by such run 95 and engaging the links of the other run near the top of the incline.

6. In a device of the class described, an 100 endless conveyer consisting of an endless series of steps connected by rack links, and comprising upper and lower inclined runs, the upper run having horizontal landing portions, a driven shaft having pinions 105 engaging the rack links near the lower end of the lower run, and an idler shaft provided with pinions driven by the upper run and engaging the rack links of the upper run near the top of the incline.

7. In a device of the class described, the 110 combination with inner and outer tracks forming a way, of a series of connected steps each having a wheel-base the arms of which are of uneven length and in the same horizontal plane, the wheels on the outer tracks being on the longer arms and such arms being bent laterally to pass over the inner tracks.

8. In a device of the class described, a 115 step unit comprising a step, an axle bar fixed thereto in advance of the center line of the tread, and a wheel-base wider than the tread and comprising oppositely extending arms fixed to the axle bar.

9. In a device of the class described, a 120 series of steps provided with axle bars in advance of the centers of the treads, links connecting the axle bars, and oppositely extending arms fixed to each axle bar and providing a wheel-base.

10. In a device of the class described, a 125 step, and a wheel base therefor comprising oppositely extending arms fixed to the step in advance of the center line of the tread.

11. In a device of the class described, an 130 enveloped rack.

12. In a device of the class described, an endless conveyer having driven racks, and an upthrust for the racks.
13. In a device of the class described, an endless conveyer provided with racks, a pinion coöperating with the racks to drive the conveyer, and an upthrust with which the racks coöperate while in engagement with the pinion.
- 10 14. In a device of the class described, a series of steps, racks connecting the steps, a pinion engaging the racks, and an upthrust with which the racks coöperate under the action of the pinion.
- 15 15. In a device of the class described, a conveyer, pinions for driving the conveyer, and an adjustable guide with which the conveyer coöperates under the action of the pinion.
- 20 16. In a device of the class described, a conveyer, pinions for driving the conveyer, and an automatically adjustable guide with which the conveyer coöperates under the action of the pinion.
- 25 17. In a device of the class described, a conveyer provided with driving racks, and a guide coöperating with the racks and permitting change of movement thereof.
- 30 18. In a device of the class described, a series of rack-connected steps, and a guide with which the back of the racks contact.
- 35 19. In a device of the class described, a conveyer provided with racks through which motion is communicated to the conveyer, and a guide contacting with the backs of the racks.
- 40 20. In a device of the class described, sections, a guide, and racks pivoted to the sections and provided with contact surfaces coöperating with the guide and located within the space between the pivot centers.
- 45 21. In a device of the class described, sections, and rack links pivoted to the sections, and each having one of the teeth thereof located in the line of the pivot center, and an upthrust to prevent tilting of the links.
- 50 22. In a device of the class described, a series of sections, rack links pivoted to the sections and having the same number of teeth, one tooth of each link being located in the line of the pivot center, and an upthrust to prevent tilting of the links.
- 55 23. In a device of the class described, sections, linkage connecting the sections and composed of male and female rack links having the same number of teeth, one tooth of each link being located in the line of its pivot center, and an upthrust to prevent tilting of the links.
- 60 24. In a device of the class described, a conveyer, driving means therefor, and yieldingly mounted means coöperating with the conveyer for resisting the thrust of the driving means.
- 65 25. In a device of the class described, a conveyer consisting of a series of link connected steps, driving means therefor, and a guide coöperating with the links for resisting the thrust of the driving means.
26. In a device of the class described, a series of steps, connecting links pivoted to the steps, a pinion engaging the links, and a guide coöperating with the links for preventing pivotal movement of the links under the action of the pinion.
27. In a device of the class described, a conveyer consisting of a series of link connected steps, driving means engaging the links, and an upthrust device coöperating with the links for resisting the thrust of the driving means.
28. In a device of the class described, link connected steps, a pinion engaging the links, and means for preventing tilting of the links under the action of the pinion.
29. In a device of the class described, link connected steps, a pinion engaging the links, and a guide adapted to coöperate with the links for preventing pivotal movement of the links under the action of the pinion.
30. In a device of the class described, a way, connected steps adapted to the way and connected by toothed links, a pinion engaging the links, and an upthrust track with which each link coöperates as its end tooth is engaged by the pinion.
31. In a device of the class described, tracks forming a way, steps connected by toothed links and adapted to the tracks, and a guide located in advance of each pinion with reference to the direction of movement of the links and with which each link is in engagement as the pinion engages the last tooth of such link.
32. In a device of the class described, an endless conveyer consisting of a series of link connected steps, driving pinions engaging the links, and a track adapted to coöperate with the links for counteracting the overturning action of the pinions.
33. In a device of the class described, an endless conveyer consisting of a series of steps and rack links connecting the steps, driving pinions engaging the links, and a track coöperating with the links to counteract the tendency of the pinions to lift the links.
34. In a device of the class described, a series of steps and rack links connecting the steps, driving pinions engaging the links, and a guide engaging the opposite side of the rack links for counteracting the lifting action of the pinions.
35. In a device of the class described, a series of steps and rack links connecting the steps, driving pinions engaging the links, and a track coöperating with the links for counteracting the lifting action of the pinions, such track being turned upwardly to guide the advancing links under the track.

36. In a device of the class described, a way, steps adapted to the way and connected by rack links having bosses, a pinion engaging the links, and a guide with which the bosses are adapted to contact under the action of the pinion.

37. In a device of the class described, a way, steps adapted to the way, rack links pivotally connecting the steps and having bosses, pinions engaging the links, and a track with which the bosses coöperate to counteract the tilting of the links under the action of the pinions, the rear boss with reference to the direction of movement being offset from the pivot of the link to avoid elevation of the link out of normal as the advancing end of the link enters a curve of the way.

38. In a device of the class described, the combination with a way having angularly disposed portions, a series of link connected steps adapted to the way, pinions engaging the links, and a guide for counteracting the tilting of the link under the action of the pinions, the end of such track being adapted to yield as the end of the link changes its line of movement.

39. In a device of the class described, the combination with a way having angularly disposed portions, a series of link connected steps adapted to the way, pinions engaging the links, and a track for counteracting the tilting of the links under the action of the associated pinion and having a yielding end to compensate for the movement of the link in passing from one portion of the way to another.

40. In a device of the class described, the combination with a way having an inclined and a horizontal portion, steps adapted to the way, links connecting the steps and provided with bosses, pinions engaging the links near the end of the incline, and a track located over each pinion and with which the bosses of the links coöperate to prevent tilting thereof under the action of the pinion, the boss at the rear end of the link being offset from the pivot center to avoid elevation of the link out of normal as the advancing end of the link passes from the incline to the horizontal.

41. In a device of the class described, a series of movable steps, links connecting the steps and alternately arranged in the same plane, a drive for the links, and an upthrust engaging alternate links.

42. In a device of the class described, a series of steps provided with axle bars, alternately arranged inner and outer links pivotally connecting the steps, the outer links being provided with bosses offset from the ends thereof, driving pinions engaging the rack links, and tracks located opposite the pinions and with which the bosses coöperate to counteract the tilting action of the pin-

ions and having yielding upwardly turned ends.

43. In a device of the class described, a series of steps connected by rack links, driving pinions engaging the rack links, and an adjustable upthrust track associated with each pinion parallel with the line of movement of the links and coöperating therewith to counteract the tilting action of the pinions.

44. In a device of the class described, a series of steps connected by rack links, driving pinions engaging the rack links, and an upthrust track associated with each pinion and coöperating with the links to counteract the tilting of the latter under the action of the pinions, such track being adjustable to and from the pinions to provide a normal clearance between the track and links.

45. In a device of the class described, the combination with a moving stairway consisting of a series of wheeled steps provided with axle bars, rack links connecting the steps, a pinion engaging the links to move the steps, and an upthrust device adapted to coöperate with the links to counteract the lifting action of the pinions.

46. In a device of the class described, a series of link-connected steps, a pinion engaging the links to move the steps, an upthrust with which the links coöperate under the action of the pinion, and means to lubricate the links.

47. In a device of the class described, a conveyer provided with links and to which motion is imparted by pushing the links.

48. In a device of the class described, a conveyer to which power is applied in driving by putting the links in compression.

49. In a device of the class described, an endless stairway consisting of steps, and rack-links pivotally connecting the steps, and pinions engaging the rack-links and putting them in compression to drive the stairway.

50. In a device of the class described, a step having its wheel-base wider than the tread thereof, the center of the wheel-base being in a different vertical plane from the center of the step.

51. In a device of the class described, a step, and wheel-carrying yokes fixed to the step at one side of the center of the tread.

52. In a device of the class described, a series of connected steps having axle-bars fixed thereto in advance of the center of the tread thereof, and wheel-carrying yokes fixed to the axle-bars.

53. In a device of the class described, a series of steps provided with axle-bars, links connecting the axle-bars, and wheel-carrying yokes fixed to the axle-bars, the axle-bar of each step being in advance of the center of the tread thereof.

54. In a device of the class described, the combination with the tracks forming a way, of a series of steps having axle-bars in advance of the center of the tread yokes provided with carrying-wheels adapted to the tracks, and connections between the steps located between the yokes and steps. 70
55. In a device of the class described, a step provided with a wheel-carrying yoke 10 having arms in the same horizontal plane, one arm of which curves from the vertical plane of the other arm to a parallel vertical plane. 75
56. In a device of the class described, a step, and a wheel-carrying yoke therefor having arms in the same horizontal plane, of which the inner portion of the arms are substantially in a common vertical plane, and the outer ends of the arms are in parallel vertical planes. 80
57. In a device of the class described, the combination with inner and outer tracks forming a way, of a series of steps having yokes the arms of which are in the same horizontal plane and are provided with wheels adapted to the tracks, the arms carrying the wheels for the outer tracks crossing the inner tracks, and links connecting the steps. 85
58. In a device of the class described, a step having a wheel-carrying yoke with arms of unequal length. 90
59. In a device of the class described, a step provided with a wheel-carrying yoke 35 the arms of which are of unequal length, the longer arm being associated with the riser of the step. 95
60. In a device of the class described, a step, and a wheel-carrying yoke with arms of unequal length, the longer arm extending beyond the riser. 100
61. In a device of the class described, the combination with upper and lower tracks forming an inclined way, of a series of connected steps, and wheel-carrying yokes the arms of which are of uneven length, the wheel on the upper track being on the longer arm. 105
62. In a device of the class described, the combination with inner and outer tracks, of a series of connected steps, and wheel-carrying yokes the arms of which are of uneven length, the wheel on the outer track being on the longer arm. 110
63. In a device of the class described, the combination with tracks, of a series of connected steps, and wheel-carrying yokes the arms of which are of uneven length, the following wheel being on the longer arm. 115
64. In a device of the class described, the combination with tracks forming a way, of a series of connected steps provided with yokes the arms of which are of unequal length and provided with front and rear carrying-wheels adapted to the tracks, the 120
- rear wheel arms being the longer and bent or curved to cross the tracks of the front wheels. 125
65. In a device of the class described, the combination with tracks forming a way, of a series of connected steps each of which is provided with a wheel-carrying yoke, one arm of which is bent over the track for the wheel on the other arm. 70
66. In a device of the class described, the combination with inner and outer tracks, of a series of connected steps having axle-bars located in advance of the center of the tread of each step, yokes fixed to the axle-bars and the front arms of which are provided with wheels adapted to the inner tracks and the rear arms of which are longer than the other arms and provided with wheels adapted to the outer tracks. 75
67. In a device of the class described, the combination with inner and outer tracks forming a way, of a series of steps having axle-bars located in advance of the center of the tread of each step, yokes fixed to the axle-bars and the front arms of which are provided with wheels adapted to the inner tracks and the rear arms of which are longer than the other arms and provided with wheels adapted to the outer tracks, the said rear arms crossing the inner tracks, and links located at the inner side of the yokes and connecting the steps. 80
68. In a device of the class described, the combination with tracks forming a way, of steps having extended axle-bars, wheel-carrying yokes having inwardly extending hubs, and links connecting the steps and pivoted on the hubs between the yokes and steps. 100
69. In a device of the class described, tracks forming an inclined way, a series of steps, wheel-carrying yokes having hubs, such steps and yokes being fixed together to provide units, and rack links pivotally connecting the hubs of such units whereby the latter are free to turn independently of the links. 105
70. In a device of the class described, the combination with tracks forming a way, a series of steps, wheel-carrying yokes rigid with the steps, hubs on the yokes, and rack links pivotally connecting the hubs. 110
71. In a device of the class described, the combination with tracks forming a way, a series of steps, wheel-carrying yokes rigid with the steps, hubs on the yokes, and links pivoted on the yokes to permit the pivotal movement of the steps independently of the links, the yokes having arms of unequal length. 115
72. In a device of the class described, the combination with tracks forming a way, of a series of steps, wheel-carrying yokes rigid with the steps, and having hubs, and male and female links pivoted on the hubs of the 120

- yokes and connecting the steps, the yokes having arms of unequal length.
73. In a device of the class described, the combination with tracks forming a way, of 5 steps having extending axle-bars, wheel-carrying yokes having hubs, links connecting alternate pairs of steps and having sleeves pivoted on the yoke hubs of such steps, and alternating links pivoted on the sleeves of the other links.
74. In a device of the class described, the combination with tracks forming a way, of 10 steps having extended axle-bars, wheel-carrying yokes having hubs interlocked with the steps, links connecting alternate pairs of 15 steps and having end sleeves pivoted on the yoke hubs of such steps, and alternating links having end collars pivoted on the sleeves of the other links.
- 20 75. In a device of the class described, the combination with tracks forming a way, of 25 steps having fixed axle-bars provided with extended ends, wheel-carrying yokes fixed to the axle-bars and having inwardly extending hubs, such hubs having tongues interlocked with the steps, inner links connecting alternate pairs of steps and having end sleeves pivoted on the yoke hubs of such 30 steps, and outer links alternating with the other links and having end collars on the sleeves of the latter links.
- 35 76. In a device of the class described, tracks forming a way, steps adapted to the way, and links connecting the steps and having lubricating bushings.
- 40 77. In a device of the class described, tracks forming a way, steps adapted to the way, and male and female links connecting the steps and providing with lubricating bushings.
78. In a device of the class described, a wheel-carrying yoke having arms and a wheel-bearing on each arm integral therewith.
- 45 79. In a device of the class described, a step yoke provided with a link bearing.
80. In a device of the class described, a step yoke provided with a link bearing and step connections.
- 50 81. In a device of the class described, steps, links pivoted to the steps, and yokes connected to the steps through the pivotal centers of the links.
- 85 82. In a device of the class described, a yoke consisting of a single unit providing link-bearing arms and wheel bearings.
88. In a device of the class described, a step having a bearing for a carrying-wheel, and a retaining washer having an extension entering the bearing and secured therein.
- 90 84. In a device of the class described, a step having a bearing for a carrying-wheel, and a retaining washer having an extension entering the bearing and secured therein by 95 a cotter pin.

85. In a device of the class described, a series of connected steps having bearings for carrying wheels, a retaining washer for each wheel having an extension entering the bearing, and a cotter pin securing the extension and located at the opposite side of the wheel. 70

86. In a device of the class described, a series of connected steps having tubular bearings, wheels on such bearings, a retaining washer having a reduced barrel extending into each bearing, and means for securing the barrel in the bearing. 75

87. In a device of the class described, a step having wheel-carrying yokes provided at the ends with tubular bearings, wheels on the bearings, retaining washers having reduced barrels entering the bearings, and pins for securing the barrels in the bearings. 80

88. In a device of the class described, a step having yokes provided at the ends with tubular bearings, wheels on the bearings, retaining washers entering the bearings and forming with the latter a lubricant containing chamber. 85

89. In a device of the class described, a step having yokes provided at the ends with tubular bearings, wheels on the bearings, a retaining washer having a barrel in each bearing and closing the opposite end thereof, 90 such barrel being reduced within the bearing to provide with the bearing a lubricant containing chamber, and the bearing having an opening leading from such chamber to the wheel. 95

90. In a device of the class described, a step provided with a bearing a step-wheel secured on the bearing by a washer, and a cotter pin passing through the base of the bearing to secure the washer. 100

91. In a device of the class described, a step provided with a bearing, a wheel on the bearing, and a cotter pin back of the wheel for securing the wheel on the bearing. 105

92. In a device of the class described, a step provided with a bearing, a retaining washer, and a cotter pin securing the washer and located away from the free end of the bearing. 110

93. In a device of the class described, a step provided with a wheel bearing, and a retaining washer secured back of the step wheel and locked against turning. 115

94. In a device of the class described, a step provided with a bearing, and a wheel retaining washer secured away from the free end of the bearing and locked against turning. 120

95. In a device of the class described, a step provided with a wheel bearing, a wheel retaining washer, and a cotter pin securing the washer away from the free end of the bearing and locking it against turning. 125

96. In a device of the class described, a step having a wheel-carrying yoke provided 130

with a tubular bearing, a wheel on the bearing, a retaining washer having a reduced barrel extending into the bearing, and a pin passing through the yoke and barrel to locate the washer and prevent the same from turning.

97. In a device of the class described, a movable hand-rail and means for automatically tightening the same.

10 98. In a device of the class described, a moving hand-rail, a guide therefor, and means for automatically tightening the hand-rail.

99. In a device of the class described, the 15 combination with a conveyer, of a moving hand-rail therefor, and means for automatically tightening the same.

100. In a device of the class described, the combination with a conveyer, of a moving 20 hand-rail therefor, and means for automatically tightening the hand-rail without changing the direction of flexure thereof.

101. In a device of the class described, a moving hand-rail, and a tightener therefor 25 contacting the rail without changing the normal direction of flexure thereof.

102. In a device of the class described, a moving hand-rail, and an automatic tightener therefor located between the terminals.

30 103. In a device of the class described, a moving hand-rail, and a tightener therefor located between the upper and lower terminals of the moving circuit.

104. In a device of the class described, the 35 combination with a conveyer, of a moving hand-rail therefor, and a pulley for automatically tightening the hand-rail.

105. In a device of the class described, a moving hand-rail, and a tightener therefor 40 consisting of a pulley under tension and located between the ends.

106. In a device of the class described, a moving hand-rail, and an automatic tightener consisting of a movably mounted pulley 45 under constant tension.

107. In a device of the class described, the combination with a conveyer, of a traveling hand-rail therefor, means for driving the hand-rail, a pulley co-operating with the 50 hand-rail and movable longitudinally of the rail, and a counter-weight for moving the pulley to tighten the hand-rail.

108. In a device of the class described, a moving hand-rail having an under-cut portion 55 adapted to engage a guide, and means for automatically tightening the hand-rail.

109. In a device of the class described, a moving hand-rail elliptical in cross section, and means for automatically tightening the 60 same.

110. In a device of the class described, a reversible conveyer a balustrade crossing the conveyer to provide a side landing at each end.

65 111. In a device of the class described, a

reversible traveling stairway with horizontal landing portions at each end, and a balustrade parallel with the stairway and crossing each landing.

112. In a device of the class described, a conveyer having a portion with bearing surfaces in the same plane, a portion with bearing surfaces in parallel planes, and a portion with bearing surfaces in the same plane, the portions in the same plane having side landings, a balustrade parallel with the conveyer and crossing its parallel planes. 70

113. In a device of the class described, a conveyer having a portion with bearing surfaces in parallel planes, and portions at the 75 ends with bearing surfaces in the same plane but at different levels, and a side landing at each level, a balustrade parallel with the conveyer and crossing its parallel planes. 80

114. In a device of the class described, a carrying run with tread surfaces in the same plane, in parallel planes, and again in the same plane, reversibly operated in either direction, a balustrade parallel with the 85 conveyer and crossing its parallel planes.

115. In a device of the class described, a carrying run with tread surfaces in the same plane, in parallel planes, and again in the same plane, reversibly operated in either 90 direction and with similar end landings, and a balustrade parallel with the stairway and crossing each landing. 95

116. In a device of the class described, a carrying run with tread surfaces in the same plane, in parallel planes, and again in the same plane reversibly operated in either 100 direction, with entrance and egress at the side, a balustrade parallel with the conveyer and crossing its parallel planes. 105

117. In a device of the class described, a carrying run with tread surfaces in the same plane, in parallel planes, and again in the same plane, reversibly operated in either direction and provided with side landings, 110 a balustrade parallel with the conveyer and crossing its parallel planes.

118. A reversible conveyer having a shunt at each end, such shunts leading to the same side. 115

119. A conveyer consisting of an inclined run and a horizontal landing portion at each end, and a shunt crossing each landing portion, such shunts leading to the same side of the conveyer.

120. In a device of the class described, a conveyer, a shunt crossing the conveyer, and a traveling hand-rail also crossing the conveyer in front of the shunt.

121. In a device of the class described, a conveyer having a horizontal landing portion, a shunt crossing the landing portion, and a traveling hand-rail passing along the side of the conveyer and extending across the landing portion in front of the shunt. 125

130

122. In a device of the class described, a conveyer having an inclined carrying portion and a horizontal landing portion, a stationary shunt at the landing portion, and a traveling hand-rail passing along one side of the conveyer and crossing the landing portion in front of and substantially parallel with the shunt.

123. In a device of the class described, a conveyer having an inclined run and horizontal landing portions at the ends of the incline, a stationary shunt crossing each landing portion, and a traveling hand-rail passing along one side of the conveyer and crossing each landing portion in front of its associated stationary shunt.

124. In a device of the class described, a conveyer having an inclined carrying portion and a horizontal landing portion at each end, and a traveling hand-rail having portions crossing both landing portions.

125. In a device of the class described, a conveyer, a traveling hand-rail having a tractive surface and providing a shunt for each end of the conveyer, and driving and deflecting pulleys with which the tractive surface only comes in contact.

126. In a device of the class described, a conveyer, a traveling hand-rail having a hand-grasp surface and a tractive surface and crossing the conveyer at each end to provide a shunt, and driving and supporting pulleys with which the tractive surface only comes in contact.

127. In a device of the class described, a conveyer, an endless hand-rail substantially elliptical in cross section cut out at one side, the said hand-rail crossing the conveyer at each end to provide a shunt, a drive pulley, and pulleys for deflecting the hand-rail from the drive pulley to its return stretch, and vice-versa, all of the said pulleys entering the hand-rail through the cut-out portion and engaging the same at such portion only.

128. In a device of the class described, a conveyer having an inclined carrying portion and a horizontal landing portion at each end of the incline, pulleys at the ends and at the same side of the landing portions, an endless hand-rail passing along one side of the incline and crossing the landing portions to the pulleys, and idlers over which the hand-rail passes from one pulley to the other.

129. In a device of the class described, a conveyer having an inclined carrying portion and a horizontal landing portion at each end of the incline, pulleys at the ends and at the same side of the landing portions, a continuous hand-rail engaging one pulley and crossing the adjacent landing to the other side of the conveyer and extending along the incline to the other landing across which it passes to the other pulley, and

idlers with which the hand-rail co-operates in passing from one pulley to the other.

130. In a device of the class described, an endless conveyer having an inclined carrying portion and horizontal landing portions at the ends of the incline, means for driving the conveyer, a shaft having idlers engaging both runs, an endless hand-rail extending along one side of the incline and crossing one or both landing portions, pulleys at the ends of the landing portions co-operating with the hand-rail, and a driving connection between the idler shaft and one of such pulleys.

131. In a device of the class described, an endless conveyer having oppositely moving runs one of which consists of an inclined carrying portion and horizontal landing portions at the ends of the incline, means for driving the conveyer, a shaft having idlers engaging both runs, an endless hand-rail extending along one side of the incline and crossing both landing portions, pulleys at the ends of the landing portions co-operating with the hand-rail, and driving connections between the idler shaft and both pulleys.

132. In a device of the class described, an endless conveyer having oppositely moving runs one of which consists of an inclined transporting portion and horizontal landing portions at the ends of the incline, driven pinions engaging one run, a shaft having idlers engaging both runs, an endless hand-rail extending along one side of the incline and crossing both landing portions to the opposite side of the conveyer, horizontal pulleys at the ends of the landing portions with which the hand-rail co-operates, sprocket wheels, connections between the sprocket wheels and the pulleys, chains engaging both sprocket wheels, a cross shaft having sprocket wheels engaging the chains, and a connection between such shaft and the idler shaft.

133. In a device of the class described, the combination with a conveyer adapted to be driven in either direction and having an inclined run and horizontal landing portions at the ends of the incline, of an endless traveling hand-rail having portions crossing and forming moving shunts for both landing portions.

134. In a device of the class described, a conveyer having an inclined run and horizontal landing portions at the ends of the incline, a traveling hand-rail passing along one side of the incline and crossing both landing portions, horizontal pulleys at the ends of the landing portions and at the opposite side of the conveyer around which the hand-rail passes, and a vertical and an angularly disposed idler at each end of the conveyer around which the return stretch of the hand-rail passes from one pulley to the other.

135. In a device of the class described, a conveyer having an inclined carrying portion and a horizontal landing portion at each end of the incline, horizontal pulleys at the ends of the landing portions, a continuous hand-rail engaging one pulley and crossing the adjacent landing to the other side of the conveyer and extending along the incline to the other landing across which it passes to the other pulley.
136. In a device of the class described, a conveyer having an inclined run and horizontal landing portions at the ends of the incline, and a traveling hand-rail passing along one side of the incline and crossing both landing portions.
137. In a device of the class described, a conveyer having an inclined carrying portion and a horizontal landing portion at each end of the incline, horizontal pulleys at the ends of the landing portions, a continuous hand-rail engaging one pulley and crossing the adjacent landing to the other side of the conveyer and extending along the incline to the other landing across which it passes to the other pulley, a driven pulley engaging the hand-grasp run of the hand-rail, a driven pulley engaging the return run, and an angularly disposed pulley for deflecting the return run from the latter pulley to the horizontal pulley to which it passes.
138. In a device of the class described, a conveyer having an inclined run and horizontal landing portions at the ends of the incline, a traveling hand-rail passing along one side of the incline and crossing both landing portions, horizontal driven pulleys at the ends of the landing portions around which the hand-rail passes, and a driven pulley engaging each run of the hand-rail, the latter pulleys and one of the horizontal pulleys deriving motion from a common source.
139. In a device of the class described, a conveyer having an inclined run and horizontal landing portions at the ends of the incline, a traveling hand-rail passing along one side of the incline and crossing both landing portions, horizontal driven pulleys at the ends of the landing portions around which the hand-rail passes, a driven pulley engaging each run of the hand-rail, and driving connections between the conveyer and the latter pulleys and one of the horizontal pulleys.
140. In a device of the class described, a conveyer, and a hand-rail therefor driven by pulleys located in different angular planes.
141. In a device of the class described, a conveyer, a traveling hand-rail therefor, and a drive for the hand-rail comprising a pulley located in a horizontal plane and a pulley located in a different plane.
142. In a device of the class described, a conveyer, a flexible traveling hand-rail therefor, rotating members in contact therewith for driving the same, said members being located in different angular planes, and means for deflecting the hand-rail from one plane to another.
143. In a device of the class described, a conveyer having an inclined carrying portion, a hand-rail, a horizontal pulley at each end of the conveyer for driving the hand-rail, separate driving connections for the pulleys, and a vertical driving pulley for the hand-rail at the top of the incline.
144. In a device of the class described, a reversible conveyer, an endless hand-rail, and a drive located at each end of the conveyer to pull the hand-rail in the direction of movement of the conveyer to avoid slack.
145. In a device of the class described, a conveyer adapted to be driven in either direction and consisting of an inclined portion and horizontal landings, an endless hand-rail adapted to move in the same direction as the conveyer, and a drive pulley for the hand-rail located at the end of each landing, whereby the serviceable stretch of the hand-rail is drawn taut in the direction of movement of the conveyer.
146. In a device of the class described, a conveyer having a landing portion at each end, a hand-rail, and driving mechanism for the hand-rail located over the landing portions.
147. In a device of the class described, a conveyer consisting of an endless series of connected steps providing an inclined transporting portion and a horizontal landing portion at each end, a hand-rail, and driving mechanism for the hand-rail located at the end of the landing portions and over the steps.
148. In a device of the class described, a conveyer having an inclined run and horizontal landing portions at the ends of the incline, a traveling hand-rail passing along one side of the incline and crossing both landing portions, pulleys at the ends of the landing portions over which the hand-rail passes, and automatically adjustable idlers about which the hand-rail passes from one pulley to the other.
149. In a device of the class described, the combination with a conveyer having a landing portion at each end, of a traveling hand-rail at one side of the conveyer providing shunts crossing both landing portions, and a traveling hand-rail at the other side of the conveyer spaced at its ends from the shunts.
150. In a device of the class described, the combination with a conveyer having an inclined carrying portion and a horizontal landing portion at each end of the incline, of a traveling hand-rail at one side of the

- incline and crossing both landing portions, a traveling hand-rail at the other side of the incline terminating at about the ends of the incline, a driven shaft, and driving connections between such shaft and both hand-rails. 76
151. In a device of the class described, the combination with a conveyer having an inclined carrying portion and a horizontal landing portion at each end of the incline, of a traveling hand-rail at one side of the incline and crossing both landing portions, a traveling hand-rail at the other side of the incline terminating at about the ends of the incline, a plurality of driving wheels for each hand-rail, a driven shaft, and connections between such shaft and the said driving wheels. 75
152. In a device of the class described, the combination with a conveyer having an inclined carrying portion and a horizontal landing portion at each end of the incline, a traveling hand-rail at one side of the incline and crossing both landing portions, horizontal drive pulleys for the hand-rail at the ends of the conveyer, a vertical drive pulley engaging each run of the hand-rail, a traveling hand-rail at the other side of the incline, drive pulleys for such hand-rail coöperating with the opposite runs thereof, a drive shaft, drive connections between such shaft and the pulleys engaging the runs of both hand-rails, and driving connections for the horizontal pulleys at the ends of the conveyer. 80
153. In a device of the class described, a conveyer having an inclined run and a horizontal landing portion at the upper end of the incline, and a traveling hand-rail passing along one side of the incline and crossing the landing portion, and a drive at each end of the hand-rail. 85
154. In a device of the class described, a conveyer having an inclined carrying portion and a horizontal landing portion at each end of the incline, a traveling hand-rail at one side of the incline and crossing both landing portions, and a traveling hand-rail at the other side of the incline terminating at about the ends of the incline. 90
155. In a device of the class described, the combination with a conveyer having an inclined carrying portion and a horizontal landing portion at each end, of a traveling hand-rail at one side of the incline and crossing both landing portions, and a traveling hand-rail at the other side of the incline terminating at about the ends of the incline, and driving means for pulling the hand-rails in either direction of movement of the conveyer. 95
156. In a device of the class described, the combination with a conveyer having an inclined carrying portion and a horizontal landing portion at each end of the incline, 100
157. In a device of the class described, a conveyer, a hand-rail therefor, a plurality of pulleys angularly disposed with reference to each other and one of which is driven, and an idler leading the rail from each pulley to the succeeding one. 105
158. In a device of the class described, a conveyer, a hand-rail therefor, and a drive for the hand-rail consisting of two pulleys placed angularly to each other, and an idler leading the rail from one of said pulleys to the other. 110
159. In a device of the class described, a series of connected steps, and a balustrade located in an oblique plane and having a vertical extension below the end of the steps. 115
160. In a device of the class described, the combination with a conveyer, of outwardly inclined balustrades at the ends of the steps. 120
161. In a device of the class described, a series of traveling steps, and balustrades located contiguous to the ends of the steps and being inclined outwardly. 125
162. In a device of the class described, a series of traveling steps, balustrades located contiguous to the ends of the steps and being inclined outwardly, and traveling hand-rails overhanging the tops of the balustrades. 130
163. In a device of the class described, an endless conveyer having oppositely moving inclined runs, and a track circuit, including a throat casting carrying the tracks for both runs. 135
164. In a device of the class described, an endless conveyer having oppositely moving upper and lower inclined runs, the upper run terminating in a horizontal landing portion, and a track circuit including a throat casting at the end of the incline and provided with tracks in continuation of the tracks of both the upper and lower runs. 140
165. In a device of the class described, a unitary section provided with curved track- 145
- age for the front and back wheel of a traveling step. 150
166. In a device of the class described, a unitary casing provided with curved tracks for the front and back wheels of a traveling step. 155
167. In a device of the class described, a unitary casting having integral tracks in extension of the inclined and horizontal tracks of a traveling stairway circuit. 160
168. In a device of the class described, a 165

- unitary casting provided with curved tracks to connect the inclined and horizontal tracks of a traveling stairway circuit for insuring accuracy in the erection of the circuit.
- 5 169. In a device of the class described, a unitary throat casting provided with tracks for both the upper and lower runs of an endless conveyer.
- 10 170. In a device of the class described, an endless series of link connected steps providing oppositely moving upper and lower runs, a track circuit including a unitary section having opposite bearings, and a shaft journaled in such bearings and having pinions meshing with the links of both runs.
- 15 171. In a device of the class described, an endless series of steps providing oppositely moving upper and lower inclined runs, links connecting the steps, a track circuit including sections at opposite ends of the steps having tracks for the upper run, a cross frame fixed to such sections and provided with bearings, and a shaft journaled in such bearings and having pinions meshing with the links of both runs, whereby accuracy in the relation of the pinions and steps is insured.
- 20 172. In a device of the class described, a track casting consisting of a bracket and integral tracks for the carrying-wheels of a moving footway.
- 25 173. In a device of the class described, a series of link connected steps provided with carrying-wheels, an inclined way consisting of track sections comprising brackets having integral upper and lower tracks for the wheels.
- 30 174. In a device of the class described, an endless series of connected steps, a portion of each step rising above the landing level as it passes to or from the free end of the same, and a covering or inclosure for the steps as they rise.
- 35 175. In a device of the class described, connected steps providing an inclined transporting run and a horizontal landing, each of said steps rising above the landing as it leaves or enters the free end of the same, and a shunt located in front of the rising steps.
- 40 176. In a device of the class described, a conveyer, and a stationary shunt therefor
- having a movable member which bears upon the carrying surface of the conveyer.
- 5 177. In a device of the class described, a conveyer, and a stationary shunt provided with a lower member which is supported vertically by the carrying surface of the conveyer and laterally by the other members of the shunt.
- 10 178. In a device of the class described, a conveyer, and a stationary shunt therefor having a lower member which floats upon the carrying surface of the conveyer.
- 15 179. In a device of the class described, a conveyer, and a shunt composed of a floating member at the bottom and a traveling hand-rail above.
- 20 180. In a device of the class described, a conveyer, and a shunt composed of a floating member at the bottom and a traveling hand-rail above and in front of the lower member.
- 25 181. In a device of the class described, a conveyer having a landing portion, a stationary shunt crossing the landing portion, and a vertically adjustable member on the shunt which floats on the conveyer, and a pin and slot connection between the parts.
- 30 182. In a device of the class described, the combination with tracks, of sections having supporting wheels adapted to the tracks, links connecting the sections, a guard for the wheels, and a guard for the links.
- 35 183. In a device of the class described, the combination with tracks, of steps having supporting wheels adapted to the tracks, links pivotally connecting the steps, guards for the wheels, and guards for the links.
- 40 184. In a device of the class described, the combination with tracks, of steps having wheels adapted to the tracks, rack-links connecting the steps, a pinion engaging the links, an upthrust coöperating with the links to resist the overturning action of the pinion, and a guard coöperating with the wheels to maintain them on the track as they pass through the curves.
- 45 In testimony whereof I affix my signature in presence of two witnesses.
- 50 CHARLES D. SEEBERGER.
- Witnesses:
- W. D. RICKARD,
H. R. MARSDEN.
